Attorney

UNITED STATES PATENT OFFICE.

HENRY W. GRAVES, OF CHICAGO, ILLINOIS, ASSIGNOR OF ONE-HALF TO JOHN F. GOODE, OF CHICAGO, ILLINOIS.

STREET-TRAFFIC SYSTEM.

Application filed August 25, 1924. Serial No. 733,904.

To all whom it may concern:

Be it known that I, HENRY W. GRAVES, citizen of the United States, residing at Chicago, in the county of Cook and State of Illinois, have invented certain new and useful Improvements in a Street-Traffic System; and I do hereby declare the following to be a full, clear, and exact description of the invention, such as will enable others skilled in the art to which it appertains to make and use the same.

My invention relates to driveway constructions for expediting traffic and reducing accidents at street intersections, and in general aims to provide a relatively simple and inexpensive construction which will not require either of these intersecting streets to be depressed, which will facilitate the making of right hand turns at the street intersection while keeping pedestrians entirely out of the path of vehicles making such facilitated right-hand turns, and which will deter the making of left-hand turns. In its preferred embodiments, it also aims to provide a construction for this purpose which will particularly expedite the through movement of automobiles along one of the intersecting streets, which will entirely prevent the making of left-hand turns close to the curbing by automobiles driving along either street, which will make it safe for passengers to reach street cars on either street from any corner of the intersection, and which will readily lend itself for use in connection with subways for pedestrians under either or both of the intersecting streets.

In my copending application No. 719,241, filed June 11, 1924, now Patent 1,515,251, issued Nov. 11, 1924, on a street traffic system, I have disclosed a street crossing construction which entirely eliminates grade crossings for both the street cars and the automobiles on the intersecting streets, and one which also will permit pedestrians to cross both streets without encountering vehicles of any kind and have claimed certain features of the same. For such purposes, my said application disclosed a street crossing construction in which one of the intersecting streets dipped under the other and which permitted right-hand turns for automobiles from three of the streets and a left-hand turn from one street to the other only. While the arrangement thus disclosed is highly desirable as a means of entirely

eliminating the risk of having pedestrians run over by vehicles of any kind, its use involves a relatively high cost owing to the needed depressing of one of the streets, which depressing is rendered all the more extensive by the required moving of the water, sewer, gas, electric light and telephone wires at the street intersection. For this reason, the cost of the construction disclosed in my said copending application may be objectionable, except at street corners where an unusually heavy vehicle traffic is encountered in both directions.

The construction here presented aims to accomplish many of the same objects at a considerably lower cost and also provides for convenient through traffic on the part of automobiles in both directions along one of the streets, thereby particularly lending itself for use at the intersections of busy through streets with cross-streets which have a relatively smaller amount of traffic on them. Furthermore, while my here presented construction does not provide special facilities for making any left-hand turns, it does provide for right-hand turns by vehicles; and in its highest development, my invention provides for the making of right-hand turns at every one of the four corners of the intersection, thereby preventing a possible confusion on the part of drivers (and particularly on the part of strangers in the city) and also conforming to the general trend towards eliminating left-hand turns.

It also lends itself more readily to the convenience of those who wish to reach, or to alight from, street cars at any one of the four corners of the intersection. Still further and also more detailed objects will appear from the following specification and from the accompanying drawings, in which

Fig. 1 is a perspective view of a street intersection, showing an embodiment of my invention.

Fig. 2 is a diagrammatic view showing the installation of my crossing system in a portion of a city in which vehicle traffic is particularly heavy on a certain through street.

Fig. 3 is a diagrammatic plan view showing a simplified embodiment of my invention designed for use at intersections where vehicles are not expected to turn into the through street.

Referring to the embodiment of Fig. 1, this

shows my street crossing system as applied to the intersection of two streets in which the street 1 is a through street having a relatively heavy traffic of vehicles on it, 5 while the traffic on the intersecting street 2 is relatively smaller. To meet the conditions at such a street crossing, I preferably provide a pair of partly inclined and partly elevated through driveways at opposite 10 sides of the through street 1 and preferably adjacent to the curbs, and also provide two pairs of inclined roadways for respectively connecting each of the aforesaid through driveways with the cross street 2. 15 Thus, Fig. 1 shows an inclined driveway 3 leading upwardly from the left-hand side of the through street 1 to an elevated driveway 4 which extends at sufficient height above the cross street 2 to permit the passage 20 of street cars, moving vans and other tall vehicles under it. It also shows an inclined roadway 5 leading downwardly from the opposite end of the elevated driveway 4, the portions 3, 4, and 5 being all desirably 25 close to the outer edge of the sidewalk 6 on that side of the street. At the opposite side of the through street 1, I likewise provide an upwardly inclined driveway 7 leading to an elevated roadway 8 from which a downward 30 incline 9 leads to the level of the street. I also provide inclines 10 and 11 leading upwardly from the cross street 2 and adjacent to diagonally opposite corners of the intersection respectively to the two elevated 35 roadways, and provide downward inclines 12 and 13 leading from these same roadways.

To prevent vehicles from making left-hand turns at the junctures of each of these 40 elevated roadways with the inclines 10 to 13 inclusive, I provide guards directed at an acute angle towards the direction in which vehicles travel along each of the said 45 through roadways which are disposed respectively along the two sides of the through street 1. For example, since the incline 7 in Fig. 1 is disposed at the right-hand of the through street 1, this will be traversed mainly by automobiles traveling up this incline 50 and continuing in the direction of the arrow 14 of that figure. Automobiles traveling up the same incline 7 can also make a right-hand turn down the incline 13 as shown by the arrow 15, and the same holds true at the 55 diagonally opposite corner where the arrow 16 shows how an automobile driving up the incline 3 can make a right-hand turn down the incline 12 to the cross street instead of continuing straight on over the crossover 60 4 to the downward incline 5. So also, an automobile driving up the incline 10 can make a right-hand turn down the incline 5 and on travelling up the incline 11, can turn to the right down the incline 9. If the 65 inclines 10 and 11 were connected to the cor-

responding elevated crossovers by wide or even right-angled junctures, an inexperienced orreckless driver might be tempted to make a left-hand turn after driving up one of these inclines. To prevent this, I 70 curve the guards 17 and 18 so as to space these junctures more widely than the inclines, thereby compelling the making of a right hand turn by the vehicles which have driven up inclines 10 and 11 respectively. 75

To avoid interfering with the free movement of pedestrians along both streets, I desirably provide spaced pillars 19 as portions of the supports for my roadway system, so that pedestrians along any of the sidewalks at the street intersection can pass freely under the roadways. 80

With the construction thus disclosed, it will be evident from Fig. 1 that the long and straight portions of my driveways will 85 afford a ready through passage along both sides of the through street entirely out of the path of all pedestrians and also out of the path of all vehicles traversing the cross street. If this through street is employed 90 also for street cars, these cars can readily be reached by the pedestrians through the archways adjacent to the sidewalks, and with streets of even average widths, strips 95 20 between each car track and the adjacent incline can also be used for the loading and unloading of street car passengers. My arrangement therefore provides greatly increased safety for street car passengers, since all automobiles on the through street will use 100 the elevated roadway, so that the street car passengers do not have to be on the guard for them. Furthermore, if trucks and other vehicles are also obliged by the local city 105 regulations to use these elevated road portions, the movement of the street cars can be greatly expedited, thereby facilitating the handling of crowds which is desirable at all times and which is particularly needed during rush hours. 110

On the cross street, the inclines would be used only for the automobiles or other vehicles desiring to make right-hand turns, while vehicles wishing to cross the through street would have to keep between the corresponding inclined roadways. However, the archways under the inclines will also afford protection for those who are waiting for, or alighting from, street cars traversing the cross-street also. All of the archways will also afford a highly desirable shelter from the rain for such waiting street car passengers, as they can wait under the archways and can reach the safety strips 20 without danger whenever the cars approach. 115 120 125

In practice, the direction in which the straight through drives extend can be varied at different intersections according to the relative amount in travel on the intersecting streets, but it will be obvious from Fig. 2 130

that this will never interfere with the making of right-hand turns by any of the vehicles entirely out of the path of pedestrians crossing the streets or waiting for street cars. Likewise, by having these through driveways extend in the same direction at a number of consecutive intersections with the same street, such as the street 1 of Fig. 2, a long and straight through drive is secured on this street, thereby greatly facilitating the traffic along such a through street. So also, by having the through drives disposed in a transverse direction at adjacent intersections of the cross streets, as shown in Fig. 15 2 for the streets B, C, D, and E, the travel on these cross streets can readily be expedited in the transverse direction. Consequently, my system can easily be adapted to the traffic conditions in any busy part of a 20 city.

However, while Fig. 1 illustrates the use of my system at every street intersection in a portion of a city and have shown a desirable arrangement of columns for supporting 25 portions of my driveways, I do not wish to be limited to these or other details of the construction and arrangement thus disclosed, it being obvious that many variations might be made without departing either from the 30 spirit of my invention or from the appended claims.

For example, in designating certain streets of any section of a city as through streets, it may also be desirable to limit the number 35 of intersections at which vehicles from the cross-streets can turn into the through streets, hence I may simplify and cheapen the construction at the other street intersections, as illustrated for example in Fig.

40 3. This shows the turn-outs omitted at the two diagonally opposite corners from which right-hand turns would be made into the through street 1 from the cross-street C, while still facilitating both the through 45 travel along the through street and the making of right-hand turns from this through street in both directions.

I claim as my invention:—

1. In a street crossing, two elevated roadways extending at opposite sides of one street 50 across the cross-street, and four pairs of inclined driveways respectively connected to the ends of the said elevated roadways, the driveways of each pair leading respectively 55 to the two streets.

2. In a street crossing, four pairs of inclined driveways disposed respectively adjacent to the four corners of the crossing with each pair disposed for affording a right- 60 hand turn at a height permitting pedestrians to pass under the same, and two elevated roadways extending respectively along opposite sides of one of the streets and each connecting the juncture of one pair of driveways with the juncture of another pair so

as to afford a straight through drive above the other street.

3. In a street crossing, right-hand turnouts respectively disposed adjacent to the four corners of the street intersection, each turnout comprising an elevated medial portion and a pair of inclined driveways connecting the said medial portion respectively with the two intersecting streets, the parts of each medial portion outside the building lines adjacent thereto being sufficiently elevated to permit the free passage of pedestrians under the same. 70

4. A street crossing construction for facilitating traffic along a through street at its intersection with a cross-street, comprising two elevated roadways disposed above the cross-street and respectively at opposite sides of the through street, two pairs of inclined driveways respectively disposed in continuation of the said elevated roadways and connecting the latter with the through street, and two pairs of transverse inclined driveways respectively disposed at opposite sides of the cross-street for connecting the opposite side portions of the latter with the elevated roadways. 80

5. A street crossing construction for facilitating traffic along a through street at its intersection with a cross-street, comprising two elevated roadways disposed above the cross-street and respectively at opposite sides of the through street, two pairs of inclined driveways respectively disposed in continuation of the said elevated roadways and connecting the latter with the through street, and two pairs of transverse inclined driveways respectively disposed at opposite sides of the cross-street for connecting the opposite side portions of the latter with the elevated roadways. 90

6. A driveway construction for expediting vehicle traffic at the intersection of two streets, comprising four driveways respectively disposed at the four corners of the intersection, each of the said driveways comprising a medial curved portion elevated sufficiently to permit pedestrians to pass under the same, and a pair of inclines respectively connecting the said medial portions; and two elevated roadways extending over one street and each connecting the medial portions of two of the said driveways; the junctures of each elevated roadway with the medial driveway portions connected by it being spaced further apart than the inclines leading to the said medial driveway portions so as to deter the making of other than right-hand turns to and from the elevated roadways. 100

7. A crossing construction for expediting vehicle traffic at the intersection of two streets, comprising a pair of through driveways extending respectively along the opposite sides of one street; each of the said driveways comprising an elevated roadway extending across the other street; and a pair of inclines disposed in substantially straight extension of the elevated roadway and connecting the latter with the first named street at points spaced from the said other street; a pair of inclines extending respectively along opposite sides of the said other street and connecting the latter with one of the elevated roadways by curves directed away from the middle of the said other streets so as to afford acute angled junctures with the elevated roadway, the said curves being relatively narrow so as to cooperate with the acute angle of the juncture in effectively preventing the making of left hand turns at either of the said junctures.
- 10 and connecting the latter with the first named street at points spaced from the said other street; and a pair of inclined roadways leading downward respectively from the two elevated roadways to the said other street and each adjoined to the corresponding elevated roadway at an acute angle, the said inclined roadways being respectively at diagonally opposite corners of the street intersection and each disposed for
- 15 20 cooperating with one incline of the adjacent driveway for affording a right-hand turn from the first named street to the said other street.
8. A crossing construction for expediting vehicle traffic at the intersection of two streets, comprising a pair of through driveways extending respectively along the opposite sides of one street; each of the said driveways comprising an elevated roadway
- 25 30 extending across the other street; and a pair of inclines disposed in substantially

straight extension of the elevated roadway and connecting the latter with the first named street at points spaced from the said other street; a pair of inclines extending respectively along opposite sides of the said other street and connecting the latter with one of the elevated roadways by curves directed away from the middle of the said other streets so as to afford acute angled junctures with the elevated roadway, the said curves being relatively narrow so as to cooperate with the acute angle of the juncture in effectively preventing the making of left hand turns at either of the said junctures.

9. A street crossing construction, including two turn-out drives respectively adjacent to the diagonally opposite corners of the street intersection; each of the said drives comprising a curved medial portion having parts thereof extending over the street portions alining with the adjacent sidewalks so as to permit pedestrians to pass freely under these parts, and two inclines respectively connecting the ends of the said medial portions with the two streets.

Signed at Chicago, Illinois, August 20th, 1924.

HENRY W. GRAVES.
